(57) **CLAIM**

The ornamental design for an ear dryer, as shown and described.

DESCRIPTION

FIG. 1 is a perspective view of an ear dryer showing our new design;

FIG. 2 is a front view thereof;

FIG. 3 is a left view thereof;

FIG. 4 is a right view thereof;

FIG. 5 is a back view thereof;

FIG. 6 is an enlarged top view thereof;

FIG. 7 is an enlarged bottom view thereof;

FIG. 8 is an enlarged view of the encircled area 8 of FIG. 2; FIG. 9 is an enlarged view of the encircled area 9 of FIG. 4; and,

FIG. 10 is an enlarged view of the encircled area 10 of FIG. 7.

The broken lines shown in the figures depict portions of the ear dryer that do not form part of the claimed design. The dot-dash broken lines represent the bounds of the enlarged views and form no part of the claimed design.

1 Claim, 10 Drawing Sheets
